FURNACE WALL CONSTRUCTION

Louis H. Hosbein, Glencoe, Ill., assignor to M. H. Detrick Company, Chicago, Ill., a corporation of Delaware

Application June 24, 1936, Serial No. 86,975

15 Claims. (Cl. 72—101)

This invention relates to improvements in the construction of furnace walls of the type wherein the furnace chamber wall is formed of refractory blocks or tiles which are supported on an external metallic framework.

One of the objects of the present invention is the provision of an improved construction for supporting the wall in sections upon the metallic framework in such fashion that the refractory blocks and tiles which make up the sections are retained in proper position and may be assembled in the wall structure, and removed therefrom for purpose of replacement, with facility.

Another object is the provision of a construction which will be effective to minimize loss of heat through the wall.

A particular object is the provision of a construction wherein the refractory wall may be effectively insulated for the purpose of avoiding loss of heat, and which is particularly adapted to facilitate the assembly of the construction and also the removal and replacement of the insulation and the wall refractories for purposes of inspection or repair.

Yet another object is the provision of an improved construction wherein an external sheathing of plate or sheet sections is carried on the metallic framework in such fashion as to constitute an effective external covering or finish sheathing which may be assembled with facility and dismounted sectionally to afford access to the insulation and the wall refractories and the members whereby they are supported on the metallic supporting members.

Other and further objects of the invention will be pointed out or indicated hereinafter or will be apparent to one skilled in the art upon an understanding of the invention or its employment in use.

For purpose of aiding in an explanation of the invention I show in the accompanying drawing forming a part of this specification, and herein-after describe, one form of structure in which the invention may be embodied. It is to be understood, however, that this is presented merely for purpose of illustration and hence is not to be construed in any fashion calculated to limit the appended claims short of the true and most comprehensive scope of the invention in the art.

In said drawing

Fig. 1 is an exterior elevational view of a portion of a furnace wall, some of the parts being shown in section and some of the parts being broken away to show interior parts;

Fig. 2 is a sectional view through a portion of

such wall, the section being taken on approximately line 2—2 of Fig. 1;

Fig. 3 is a side elevational view of a slab-retaining member employed in the wall construction;

Fig. 4 is a detail showing a section at line 4—4 of Fig. 1;

Fig. 5 is a detail showing a section at line 5—5 of Fig. 1; and

Fig. 6 is a face view of a refractory block tile employed in the construction.

An understanding of the invention will be most quickly had from a detailed explanation of the construction here illustrated, which will now be described.

The principal load-carrying members of the wall structure are columns 10, which are structural steel members preferably of I-cross-sectional form. These are arranged in upright position at intervals along and exterior of the furnace chamber and have suitable foundation support at their lower ends. To the inner flanges 10a of the column members 10 are secured transverse frame members 11, which extend horizontally from one column member to another. These transverse frame members are made of a suitable heat resistant material, such as cast iron, and are provided with top and bottom flanges extending both inwardly and outwardly, and also with an upwardly extending bracket-retaining flange 11a. They are mounted on the flanges 10a of the column members by means of bolts 12 which pass through said flanges, and they are provided with bolt holes 11b at intervals along their length. Each adjacent pair of column members thus supports a plurality of transverse frame members 11 one above another at the side toward the furnace chamber.

On each of the transverse frame members 11 is mounted a series of brackets or hangers 14, which are made of a suitable strong heat resistant material such as cast iron. Each hanger comprises a plate-like body portion having a hook 15 adapted to engage the outer side of the flange 11a and rest on top of the horizontal supporting member 11. The body portion also has a foot 16 adapted to abut the inwardly extending flange at the lower edge of the frame member 11. Thus the bracket is supported in upright position on the transverse frame member. The body member 14 extends for a distance inwardly from the transverse frame member and is formed with a downwardly extended arm 17 and a narrow laterally projecting shelf 18 at each side. At its inner margin the body portion and leg 17 are provided

with laterally extending lugs 19, 20, 21, and 22 projecting from each side. The lugs 19 and 21 are in alignment with one another longitudinally of the body portion, while the lugs 20 and 22 are likewise in alignment with each other but offset inwardly of the body portion from the aligned lugs 19 and 21. These brackets, supported on the transverse frame members 11 as above described, are arranged with those on one frame member in vertical alignment with those on the subjacent or superjacent frame member.

The refractory wall is built up of refractory tiles which, for the most part, may be of the form shown in Fig. 6, with series of projections 24 and seats 25 on portions of their top, bottom and side faces. Adjacent their outer ends these tiles, which are designated by the numeral 23 in Fig. 2, are provided with lateral grooves 26 and 26a, the width of said grooves being but slightly 10 in excess of the overall distance between the remote vertical sides of the bracket lugs 20 and 21.

The arrangement of the refractories and brackets is in general the same as that shown and described in my copending application Serial No. 25 26,766, filed June 15, 1935 for Furnace construction. The horizontally associated brackets 14 are spaced at intervals corresponding to the width of two of the tiles 23 and each horizontal row of brackets supports a wall section independently 30 of the section below it. At the bottom of each section is a row of base tiles 27, each of which is of sufficient width to span the distance between two of the brackets, its sides resting on the shelves 18 thereof. The tiles 27 are grooved at 35 their sides, said grooves accommodating the lugs 20 and lowermost lugs 21 of the brackets. The lug 20 contacts one side of the tile groove and the lug 21 the opposite side, and thereby the tile 21 is retained against tilting, its inner end portion projecting for a substantial distance inwardly from the brackets. The lowermost course of tiles 23 is laid on the tiles 27, said tiles being arranged in pairs between the adjacent brackets, the groove 26 of one tile of the pair being engaged with the lug 22 and the intermediate lug 21 of one of the brackets, and the groove 26a of the other tile of the pair being likewise engaged with those lugs of the adjacent bracket. The tiles 21 extend inwardly for a substantial 40 distance beyond the inner ends of the base tiles 27, and they are retained against tilting by engagement of the lugs 22 and 21 with opposite sides of the tile grooves. The section is then built on upwardly with additional courses of tiles 45 23 arranged as described in the above mentioned copending application, some of the tiles in the upper courses of the section being engaged with the lugs 19 of the superjacent brackets, and the projections and seats of the tiles in one course being intermeshed with those of the tiles in subjacent and superjacent courses. At the top of the section short tiles 28 fill the space between the inner ends of the base tiles 27 and the inner ends 50 of the tiles 23, and layers of refractory joint packing material 29 are interposed between the uppermost tiles in one section and the lowermost tiles of the superjacent section to seal the joint and allow for vertical expansion. By virtue of the 55 intermeshing engagement of the tiles and the anchorage, connection of some of them with the brackets, the inner and outer ends of the tiles are retained in alignment vertically.

To insulate the refractory wall for the purpose 60 of preventing loss of heat from the furnace cham-

ber, I provide slabs 30 and 31 of insulating material. These slabs are of size convenient for handling, the slabs 30 preferably being of a height corresponding to the vertical spacing of the brackets 14 and of a width corresponding to the horizontal spacing of said brackets, and the tiles 31 preferably being of a height corresponding to the height of the body portion of the brackets and of a width corresponding to the horizontal spacing of the brackets. The slabs are placed 10 against the outer ends of the wall refractories, the slabs 30 resting at their lower ends on top of the brackets and the slabs 31 being disposed between the brackets and resting on top of the slabs 30. The slabs are retained in place against the wall 15 refractories by holders 32. These are rigid plate-like members and may be made of cast iron. They are somewhat longer than the slabs 31, and on their backs or outer sides have wedge-shaped 20 projections 32a. These slab holders are inserted 25 downwardly between the transverse frame members 11 and the slabs, each holder overlapping three of the vertically associated slabs, and the wedge member 32a engaging the frame member 11. Accordingly, the holding member may be driven down to such an extent as may be necessary to hold the slabs against the outer ends of the wall refractories.

To provide an outside finish sheathing or casing and an insulating dead air space, I employ 30 a plurality of sheet or plate sections 34. These are somewhat wider than the distance between the flanges 10a of juxtaposed column members, and somewhat shorter than the vertical distance 35 between the bolts 12. For mounting them in place, I place bolts 35 in the bolt holes 11b of the transverse frame members, securing them in place by nuts 36. The sheet sections 34 are inserted between the adjacent column members 40 until their lateral marginal portions come to rest upon the flanges 10a, their lower margins being supported on the bolts 35. Batten strips 37 which are punched to receive the bolts 35 are then threaded thereon in overlapping relationship to the marginal portions of the adjacent sheet sections 34. Batten clamps 38 are provided, each being shaped to accommodate the end portion of a batten strip 37 and to fit against the flange 10a and web 10b of the column member and also being apertured to accommodate a bolt 12. Angular sheet clamps 39 are provided, same being shaped in conformity with the angular relationship of the flange and web of the column member, and being apertured for accommodation of the bolt 40. One or more of the sheet clamps 38 are disposed at each lateral margin of a sheet section 34, the web of the column member being punched to accommodate the bolt 40.

It will be appreciated that the flanges of structural steel members, such as I-beams, are customarily thinner at their margins than at the web, and consequently that their inner surfaces are not at right angles to the web. The plate-engaging faces of the batten clamps 38 and sheet clamps 39 are shaped to correspond to this bevel of the inner faces of the flanges 10a. Accordingly, when the nuts on the bolts 12 and 40 are set up tightly against the clamps, the marginal portions of the sheet section will be pressed into tight engagement with the flanges 10a, with the result that the sheet sections, and also the battens 37 when the nuts are set up on the bolts 35, will be given a slight inward camber. Thus the margins of the sheet sections will be tightly 70 75 80 85 90 95 98 99 100

clamped against the column flanges 10a and between batten strips and the flanges of the transverse frame members 11, with the result that the casing or sheathing will be very tight and prevent any substantial infiltration of air into the space between the sheathing and the insulating slabs. Thus this space may constitute a dead air space which will afford additional heat insulation for the refractory wall. If desired, instead of utilizing this space as a dead air space, it may be utilized for a controlled circulation of air.

From the foregoing it will be appreciated that the construction is one which provides very effective insulation for the refractory wall, but at the same time permits the structure to be assembled with facility and admits of parts being readily removed and replaced for purposes of inspection or incident to replacement of refractories. The sheathing panels and the insulating slabs are of sizes which can be handled easily, and the manner in which they are mounted and secured in place permits their being demounted and re-assembled intact.

What I claim is:

- 25 1. In a furnace wall, in combination, spaced upright members, transverse frame members supported laterally on said upright members, refractories supported by said transverse frame members to form a furnace chamber wall spaced laterally therefrom, removable heat insulating slabs applied to the outer surface of said refractories, and slab holders retained by said transverse frame members and holding the slabs against the refractories.
- 30 2. In a furnace wall, a structure as specified in claim 1 and wherein some of the insulating slabs are interposed between the refractories and the transverse frame members.
- 35 3. In a furnace wall, a structure as specified in claim 1 and wherein the insulating slabs are disposed one on top of another and respective slab holders have retentive engagement with a plurality of slabs.
- 40 4. In a furnace wall, in combination, spaced upright members, transverse frame members supported laterally on said upright members, brackets supported on said transverse frame members, refractories supported by said brackets to form a furnace chamber wall spaced laterally from the transverse frame members, demountable heat insulating slabs applied to the outer surfaces of said refractories, and slab holders retained by said transverse frame members and holding the slabs against the refractories.
- 45 5. In a furnace wall, a structure as specified in claim 4 and wherein the brackets have anchoring engagement with some of the refractories to retain them against movement inwardly away from the transverse frame members.
- 50 6. In a furnace wall, a structure as specified in claim 4 and wherein the brackets have anchoring engagement with some of the refractories to retain them against movement inwardly away from the transverse frame members and the slab holders have wedging cooperation with the transverse frame members and slabs.
- 55 7. In a furnace wall, a structure as specified in claim 4 and wherein some of the insulating slabs are interposed between the refractories and the transverse frame members.

8. In a furnace wall, a structure as specified in claim 4 and wherein the insulating slabs are arranged end to end and side by side and respective slab holders have retentive engagement with a plurality of slabs.

9. In a furnace wall, a structure as specified in claim 1 and including also a sheet sheathing secured to the upright members in spaced relationship to the insulating slabs to afford an intervening air space.

10 10. In a furnace wall, a structure as specified in claim 1 and wherein sheet panels are retained by the upright members to form a sheathing in spaced relation to the insulating slabs and fastening means for said panels are secured to the transverse frame members.

11. In a furnace wall, in combination, upright supporting members arranged in spaced relationship and having laterally extending flanges at their inner sides, a refractory wall supported by said upright supporting members in inwardly spaced relationship thereto, sheet panels disposed one above another with their lateral margins overlapping the outer surfaces of laterally extending flanges of adjacent upright members, batten strip overlapping the adjacent margins of vertically adjacent panels, and clamp members bolted to said laterally extending flanges and cooperating therewith to clamp the ends of the batten strips and marginal portions of the panels between said flanges and said clamp members, said panels and batten strips forming a sheathing spaced outwardly from the refractory wall to afford an intervening air space.

12. In a furnace wall, a structure as specified in claim 11 and including transverse frame members connected to the flanges of the upright members and supporting sections of the refractory wall, and fastening members secured to said transverse frame members at intervals lengthwise thereof and securing the batten strips thereto.

13. In a furnace wall, a structure as specified in claim 11 and wherein the outer surfaces of said laterally extending flanges are oblique to the plane of the wall and the clamping of the opposite margins of the panels against said flanges gives the panels an inwardly bowed form.

14. In a furnace wall, a structure as specified in claim 11 and wherein said upright members have webs extending outwardly from said laterally extending flanges, and sheet clamps are bolted to said webs between vertically adjacent clamp members and clamp lateral marginal portions of said panels against the outer surfaces of said flanges.

15. In a furnace wall, in combination, a bracket having an upright body portion with a laterally projecting shelf, laterally projecting lugs on said body portion disposed at different distances above said shelf, the lower lug being offset inwardly of the wall relative to the superjacent lug, and a refractory tile disposed in overlapping relationship to said shelf, said tile having a slot accommodating said lugs, the lower lug engaging the inward wall of the slot and the upper lug engaging the outward wall of the slot, whereby the tile is retained against tilting inwardly.

LOUIS H. HOSBEIN.
